(57) **CLAIM**

We claim the ornamental design for a knob, as shown and described.

DESCRIPTION

FIG. 1 is a top view of the knob according to the claimed design;

FIG. 2 is a bottom view the knob according to the claimed design;

FIG. 3 is a left side view of the knob according to the claimed design;

FIG. 4 is a right side view of the knob according to the claimed design;

FIG. 5 is a front side view of the knob according to the claimed design;

FIG. 6 is a rear side view of the knob according to the claimed design; and,

FIG. 7 is a top perspective view of the knob according to the claimed design.

The broken lines in the drawings are for illustrative purposes only and form no part of the claimed design.
